UNITED STATES PATENT OFFICE.

GEORGE B. BOSCO, OF CHICAGO, ILLINOIS.

ADJUSTABLE SHORE.

Application filed January 30, 1924. Serial No. 689,419.

To all whom it may concern:

Be it known that I, GEORGE B. Bosco, a citizen of the United States of America, and a resident of Chicago, in the county of Cook and State of Illinois, have invented a new and useful Improvement in Adjustable Shores, of which the following is a specification.

The main objects of this invention are to provide an improved form of adjustable shore; to provide improved means for quickly obtaining a rough adjustment of approximately the correct length and subsequently obtaining a fine adjustment; to provide a shore which is readily collapsible; to provide improved means for locking the separate parts of the shore together so that, when the shore is repeatedly used for work of uniform requirements, it may, if desired, be transported without disturbing the rough adjustment; to provide an improved shore of this kind which is especially adapted for use in temporarily supporting concrete floor forms; and to provide a device of this kind which is easy and certain in operation so that it may be used even by unskilled labor.

An illustrative embodiment of this invention is shown in the accompanying drawings, wherein—

Fig. 1 is a front elevation of the shore, partly broken away for the sake of clearness.

Fig. 2 is a side elevation of the same, taken from the right of Figure 1 and partly broken away.

Fig. 3 is an enlarged transverse section, taken on the line 3—3 of Figure 1.

Fig. 4 is an enlarged detail in elevation, showing the wedges for obtaining the fine adjustment of the shore.

Fig. 5 is a transverse section, taken on the line 5—5 of Fig. 4.

Fig. 6 is a fragmentary detail, in section, of the lower part of the shore, showing the relative positions of the wedges when the shore is collapsed.

Fig. 7 is a sectional detail showing a modification of the means for locking the upper post to the frame.

Fig. 8 is a detail, partly in section, showing a modification of the means for locking the lower post to the frame.

The majority of adjustable shores heretofore in use involve either a screw jack or a rotatable cam for relatively shifting the adjustable parts to expand or contract the shore. Such constructions are not entirely satisfac-

tory for the reason that the operating mechanism requires oiling and is liable to be rendered inoperative by being clogged with concrete when the shore is used in concrete construction work. Moreover, such devices are expensive to manufacture and generally require a special tool for their operation.

These disadvantages of prior devices are overcome by the present invention which, in the specific embodiment herein illustrated, is applied to a shore wherein the posts are connected together by an improved form of frame having means for supporting one of the posts in various positions along said frame for obtaining a rough adjustment of the shore. A fine adjustment is obtained by an improved form and arrangement of wedges which bear between the frame and the other post. With this improved construction, the device may be finally adjusted by tapping one or both of the wedges, and it may be quickly collapsed by a single tap of the hammer on one of the wedges. In the construction herein shown, improved means is also provided for locking the separate parts of the shore in their assembled relation, so as to permit the device to be transported in either its collapsed or its roughly adjusted position.

As illustrated the shore comprises a pair of posts 1 and 2, and a frame structure 3 adjustably supported on the post 1 by means of wedges 4, and which in turn support the post 2 by a pin 5 which is adjustable to various positions along said frame for obtaining a rough adjustment of the shore prior to the final exact setting obtained by the expansion and contraction of the wedges.

The posts 1 and 2 are slidably arranged within the frame 3, and project beyond the opposite ends thereof. When the shore is used in an upright position, the post 1 forms the base on which the frame 3 is supported, and the post 2 forms the support for the work, not shown. The posts 1 and 2 are preferably timbers of standard thickness, to which the usual braces, not shown, may be readily nailed if desired. If desired, the base 1 may also be nailed to the floor, after the shore has been finally adjusted, to secure the device against lateral slippage. Mounted on the inner ends of the posts 1 and 2, are bearing plates 6, which are secured thereto by rivets 7 or other suitable fastening means.

In the specific construction herein shown,

the frame 3 comprises a pair of channel members 8, which are arranged in opposed relation so as to form guideways for the posts 1 and 2. The channel members 8 are rigidly secured together in spaced relation by collars 9, which embrace the frame at the ends thereof, and plates 10 located intermediate its ends. The plates 10 are staggered, as shown in Fig. 2, so as not to interfere with the raising of the post 2, which is generally accomplished by inserting the operator's hand through the space 11 between the channel members.

Extending through the channel members 8 and spaced apart longitudinally thereof, is a plurality of apertures 12, arranged to receive the pin 5, which is thereby adjustable to various positions along the frame for obtaining the rough adjustment of the shore. The pin 5 is provided with a handle 13 at one end thereof, and is threaded at its other end to receive a nut 14. Also formed in the channel members 8, is a pair of slots 15 arranged in opposed relation to form an opening for receiving the wedges 4. The wedges 4 are formed so as to provide coacting inclined cam faces 16, and substantially parallel edges 17. The edges 17 bear against the bearing plate 6 of the post 1, and shoulders 18 formed at the upper ends of the slots 15, so that by driving one or both of the wedges inwardly the post 1 and frame 3 are relatively shifted to expand the shore. This construction and arrangement of parts permits a very fine adjustment of the shore after the rough adjustment has been made by the pin 5. In order to secure the wedges 4 against slippage after the shore has been set up, the cam faces 16 are transversely grooved so as to be adapted to form keyways for the reception of a locking key 19. The grooves may be arranged in various positions along the cam faces 16, but the arrangement shown in Fig. 4 has been found preferable. In this construction, one of the wedges is provided with only two grooves 20 adjacent each end of the cam face 16, whereas the other wedge is provided with a series of grooves 21 adjacent each end thereof. Either one of the grooves 20 is adapted to register with any one of the grooves 21 in the opposed series. As clearly shown in Fig. 4, the grooves 20 are differentially spaced with respect to the grooves 21, so as to permit an adjustment of the wedges different than the spaces between the grooves 21. Mounted on opposite sides of the wedges, are shoulders 22 arranged to coact with the inner faces of the channel members 8 for securing the wedges against removal from the frame.

Referring to Figures 1 and 2, the improved means for locking the posts 1 and 2 to the frame 3 so as to permit the device to be transported in either its collapsed or

roughly adjusted position, comprises a pair of substantially U-shaped straps 23 and 24 embracing the ends of the posts 1 and 2 respectively and secured thereto by rivets 25 or other suitable fastening means. The strap 23 straddles the wedges 4 and passes over a sleeve 26 mounted on a pin 27 extending through the frame 3. The sleeve 26 secures the post 1 against removal from the frame 3 and also serves as a spacer and brace for the channel members 8. The strap 23 is of sufficient length so as not to interfere with the expansion of the shore. The strap 24 embraces the pin 5 for securing the post 2 against withdrawal from the frame 3.

In the modification shown in Fig. 8, the strap 23 is omitted and the post 1 is secured against removal from the frame 3 by means of a bolt 23.1 which extends transversely through the post 1 in position to coact with the lower collar 9 when the post 1 drops in the frame.

In the modification shown in Fig. 7, the strap 24 is omitted and the bearing plate 6 of the post 2 is provided with a downwardly extending lug 24.1 having an aperture 24.2 for receiving the locking pin 5.

In operation, an approximate length of the shore is obtained by suitably locating the pin 5 in the frame 3. The final exact setting is made by driving one or both of the wedges 4 inwardly the desired distance and then inserting the key 19 into the keyway formed by the two registering grooves in the cam faces 16. To take down the shore, the key 19 is removed and the wedges 4 may then be loosened by the blow of a hammer or other suitable tool. To collapse the shore, the pin 5 is removed and inserted into the lowermost aperture 12 for locking the post 2 in its innermost position.

In concrete construction work, it is frequently desirable to use the same shores repeatedly for work of uniform requirements. For instance, in building the so-called "typical" floors, which are of uniform height, the shores are removed from one floor as soon as the concrete has properly set, and are then set up on another floor. Heretofore it has been necessary to readjust the shores each time they are set up. With the present construction, the pin 5 locks the post 2 to the frame 3 so that, if desired, the shore may be transported from one job to another without disturbing the rough adjustment.

Although but one specific embodiment of this invention has been herein shown and described, it will be understood that numerous details of the construction shown may be altered or omitted without departing from the spirit of this invention as defined by the following claim.

I claim:

An adjustable shore comprising a hollow upright frame having an opening extending

transversely therethrough, a pin extending transversely through said frame above said opening, a post telescopically arranged in the lower end of said frame and having its upper end located adjacent said opening, a substantially U-shaped strap mounted on said post and extending around said pin for securing said post against withdrawal from said frame, a pair of coacting wedges extending into said opening from opposite sides of said frame and arranged to coact with said frame and post for expanding the shore, and shoulders on said wedges arranged to coact with said frame to secure said wedges against withdrawal from said frame.

Signed at Chicago this 28 day of January, 1924.

GEORGE B. BOSCO.
